UNITED STATES PATENT OFFICE

165,032

HEATER

Edward B. Vandas, St. Louis, Mo., assignor to
American Stove Company, St. Louis, Mo., a cor-
poration of New Jersey

Application October 24, 1950, Serial No. 12,703

Term of patent 14 years

(Cl. D81—19)

To all whom it may concern:

Be it known that I, Edward B. Vandas, a citizen of the United States, residing in St. Louis, Missouri, have invented a new, original, and ornamental Design for a Heater, of which the following is a specification, reference being had therein to the accompanying drawing, forming a part thereof.

Fig. 1 is a view in front elevation of a heater, embodying my new design,

Fig. 2 is a top plan view,

Fig. 3 is a view in elevation of one end,

Fig. 4 is a view in elevation of the opposite end, and

Fig. 5 is a rear view thereof.

The openings which are only partially illustrated extend throughout the panelled areas where shown.

I claim:

The ornamental design for a heater, as shown and described.

EDWARD B. VANDAS.
